UNITED STATES PATENT OFFICE.

ROBERT R. METZ, OF CHICAGO, ILLINOIS.

ANNUNCIATOR.

1,226,683.

Specification of Letters Patent. Patented May 22, 1917.

Application filed July 24, 1916. Serial No. 110,865.

To all whom it may concern:

Be it known that I, ROBERT R. METZ, a subject of the Emperor of Germany, residing at Chicago, in the county of Cook and State of Illinois, have invented certain new and useful Improvements in Annunciators, of which the following is a specification.

The essential object of this invention is to provide an annunciator for automobiles adapted to be placed at the rear end of the car but controlled from the driver's seat, enabling the driver of a car that is equipped with this invention to indicate for the benefit of those following him what direction the driver of the car so equipped intends to take.

In the drawings, Figure 1 is a front elevation of the annunciator, meaning that said figure shows an annunciator as it appears from the rear of the automobile to which the annunciator is attached; Fig. 2 is a front view of the annunciator, the outer casing being removed; Fig. 3 is a section on the line 3—3, Fig. 2; Fig. 4 is a section on the line 4—4, Fig. 2; Fig. 5 is a detail in section on the line 5—5, Fig. 3; Fig. 6 is a detail in section on the line 6—6, Fig. 2; Fig. 7 is a detail in section on the line 7—7, Fig. 3; and Fig. 8 is an enlarged sectional detail on the line 8—8, Fig. 3.

The annunciator is provided with an outer shell or casing 1 within which the operating parts are adapted to be retained. The customary ruby light 2 and lamp 3 for illuminating the same are placed near the top and above the spacing 4 where the license plate can be secured. The casing 1 comprises back and front plates which are cross-connected at sundry places by webs 5 and 6, but the sides 7 and bottom 8 are open in order to permit the annunciating devices to be exposed from time to time.

Pivoted to one wall of the casing at 9 is a swinging-arm 10, and upon the other side of the annunciator is a similar pivot 11 carrying the similar arm 12. At the bottom of each of the two arms 10 and 12 are shells 13 and 14 which are substantial duplicates of each other and only one of which will be described. At its front, shell 13 carries a pane of glass or transparent material 15, which bears the word "Left," "Right," or some other designation, and when the parts are in the position indicated in Fig. 2, the shell 13 is invisible, being concealed by the front wall of the casing 1, but since the arm 10 and the shell 13 supported thereby is

adapted to rock upon the pivot 9 as an axis until it reaches the dotted line position, Fig. 1, the driver can elevate the arm 10 and casing 13 (or arm 12 and casing 14) to the dotted line position, Fig. 1, and thus indicate in which direction he intends to turn. Inside of the shell 13 is a lamp 16 adapted to be lighted at night, rendering the word or words upon the panes 16 visible. Helical springs 17 tend normally to return the arms 10 and 12 and the parts carried thereby to the position of Fig. 2. At the upper end of arm 10 is a pulley 18 to which one end of a rope or cord 19 is secured, said rope 19 passing over pulley 20 and extending from said pulley 20 to a lever (not shown) within easy reach of the driver. Arm 12 is provided with a similar pulley 20 connected to a cord 21 passing over pulley 22 and extending, also, to the driver, while a third pulley 23 receives the cord 24 which controls the vertically-moving shell 25 (marked "Stop"), all of said pulleys 20, 22, and 23 being journaled upon a common axis 27.

In order to avoid unnecessary waste of current, the lamps within the shells 13, 14, and 25 are ordinarily not lighted, but means presently to be described are provided to close the circuits and thereby light said lamps only when the respective shells are exposed and moved to dotted line position, Fig. 1, as they will be from time to time as the driver actuates one or more of the ropes 19, 21, and 24.

Instead of swinging the shell 25 from a vertical to horizontal position, the same is vertically reciprocated, being carried from the full-line position to the dotted line position of Fig. 1. To said shell 25 the vertically-movable slide 28 is secured, which said slide 28 bears the projection 29 which passes through or beneath the guides or straps 30, members 28 and 29 being insulated from the casing 1. The springs 17 which are secured at 31 and 32 to the swinging-arms 10 and 12, respectively, are both fastened at 33 to the slide 28, and since the springs are disposed obliquely to the longitudinal dimension of the slide 28, said springs 17 normally will pull shell 25 and the parts which support the same upwardly, and hold same in the full-line position. The rope 24 is secured at 34 to the slide 28, and when the end of said rope which is actuated by the driver is moved so that the rope travels in the direction of the arrow, Fig. 3,

the shell 25 and the slidable parts which support the same are depressed and carried to the dotted line position, Fig. 2.

As previously stated, there is a lamp 16 within the shell 13 and a similar lamp within the shell 14. The socket in which lamp 16 is mounted is so constructed that the positive current entering the lamp passes through suitable conductors insulated from the shell, while the negative current is permitted to return to the battery (not shown) or other source of current supply through the shell itself and through wires or conductors in electrical connection therewith. Inside of the shell 13 the sleeve 35 is secured, being protected by a jam-nut 36, the lower end of sleeve 35 being screw-threaded to receive the lamp 16. Insulation 37 is interposed between the shell 35 and the conductor 38, the bottom end of said conductor 38 being adapted to bear against the button 39 carried on the lamp, the screw-threaded outer surface 40 of the lamp and button 39 being insulated from each other as is customary in lamp construction. As best shown in Fig. 6, the casing 1 is provided with shouldered recesses 41 within which the conductor 42 is placed, said conductor 42 being secured to the binding-post 43 to which the positive wire 44 is connected. Insulating members 45 and 46 prevent contact of the conductor 42 with the casing 1, and at its lower end conductor 42 bears a cap or housing 47 within which the helical spring 48 is retained, said spring being adapted to keep the plunger 49 normally pressed downward. When the arm 10 is raised to the dotted line position the top end (Fig. 7) of the conductor 38 will strike the spring-controlled plunger 48 and in that manner current from the wire 44 will enter the lamp, the current passing successively through the conductors 42, 47, 49, 38, and 39 to the lamp. After having passed through the filament of the lamp the current will return to the battery through the shell 40, sleeve 35, shell 13, arm 10, and stud or pivot 9 to the main casing 1. This casing bears the boss 50 and binding-post 51 from which the wire 52 extends. The lamp within the shell 14 is adapted to be lighted in the same manner.

The circuit for the lamp within the shell 25 is somewhat differently constructed, however, the parts being arranged to close the circuit when the shell is in exposed or dotted line position and to open the circuit under other circumstances. The wires 44 which light the lamps within the swinging or rocking shells 13 and 14 both extend to the cable 53, and a wire 54, which likewise extends to said cable 53, forms part of the circuit for the lamp 55 within the shell 25. As best shown in Fig. 8, the shell 1 is insulated at 56 and 57 from the spring-brush 58 made of brass or other conducting material. A con-

tact surface 59 engages said spring-brush 58 and slides vertically therealong establishing electrical contact from time to time between the two members. Said contact surface 59 is secured to a conducting binding-post 60 from which the wire 61 extends, being fastened thereto by the knob 62. The binding-post 60 is mounted upon the slide 28, which is made of conducting material, suitably insulated from the binding-post 60 at 64. The lamp 3 within the shell 25 may be mounted as indicated in Fig. 5, which figure indicates, also, the mounting of the lamp 3 behind the ruby glass 2. The wire 61 is connected to a conductor 65 insulated at 66 from the shell 1 (or shell 25 as the case may be), which conductor 65 connects with one pole of the lamp 3, the lamp being received within the socket 67 which is in electrical connection with the shell 1 or 13. Current entering through the wire 61 will pass from the filament of the lamp and return to the battery through the socket 67 to the shell 1 or 25.

Secured upon the outer casing 1 and in electrical connection therewith, is an angle-bracket 68 formed of some conducting material, and upon the slide 28 another angle-bracket 69 is placed, likewise made of conducting material, the bracket 69 being suitably insulated from the wire 61 but in electrical contact with the slide 28. The wire 54 is in electrical connection with the spring-brush 58, so when the shell 25 and supporting parts therefor are moved to the dotted line position, the angle-bracket 69, moving vertically with the slide 28, will strike the angle-bracket 68 secured upon the casing 1, and thus close the circuit, for the current will pass successively through the wire 54, spring-brush 58, head 59, binding-post 60, wire 61, and post 65 to the lamp. Returning, the negative current will pass through the shell 25, arm 28, angle-bracket 69, angle-bracket 68, and casing 1, from which it will return to the battery.

The operation of the annunciator is as follows:

The parts normally are in the positions respectively depicted in Fig. 2 with the various hollow shells 13, 14, and 25 retained within the casing 1. If the driver of the car bearing the annunciator wishes, for example, to turn to the left, he pulls upon the rope 19, thus moving said rope in the direction of the arrow, Fig. 3, and this causes the arm 10 and shell 13 to swing about the pivot 9 as an axis until the position indicated in dotted lines in Fig. 1 is attained. The driver of any car or cars which may follow will see this sign and will be governed accordingly. As the shell 13 swings upwardly, the conductor 38 will engage the spring-controlled plunger 49, thus closing the circuit through the lamp 16 and light- 130

ing said lamp. The object of providing the spring-controlled plunger 49 instead of an unyielding member against which conductor 38 may strike, is to permit the parts to adjust themselves as will be required from time to time, and insure a perfect electrical contact notwithstanding the irregularities in the size and shape of the different parts and similar difficulties encountered in actual practice.

To operate the shell 14 which is marked "Right," the rope or cable 21 is pulled by the driver, causing the shell 14 to move to the dotted line position. When the driver of the car that bears the annunciator desires to stop, however, he pulls upon the rope or cable 24, thus depressing the shell 25 which will move downwardly until it reaches the dotted line position of Fig. 1, at or about which time the angle-bracket 69 will strike the angle-bracket 68, thus closing the circuit and lighting the lamp 3 within the shell 25. The various parts will remain in dotted line position only so long as the driver retains his grasp upon the particular rope or cable 19, 21, or 24, which he may have actuated, because the parts will all be normally returned to starting or full-line position because of the contraction of the helical springs 17, one or both of which are expanded whenever any one of said cables or ropes is pulled and the parts controlled thereby moved to dotted line position.

I claim as my invention:

- 35 1. An annunciator comprising a casing, an annunciating member pivoted therein, a second annunciating member also pivoted therein, said annunciating members being movable in directions opposite to each other, means to cause said annunciating members to swing about their respective pivots and thereby become exposed, and a third annunciating member which is slidable within said casing, means being provided to slide said last-mentioned annunciating member, whereby to expose the same and during the exposure thereof, to positively hold said first and second mentioned annunciating members in retracted position.
- 50 2. An annunciator comprising a casing, an annunciating member pivoted therein, a second annunciating member also pivoted therein, said annunciating members being movable in directions opposite to each other, means to cause said annunciating members to swing about their respective pivots and thereby become exposed, a third annunciating member which is slidable within said casing, means being provided to slide said last-mentioned annunciating member, thereby to expose the same, and a spring connecting said first and second annunciators to the

third, whereby outward movement of said third annunciator positively retracts the other two annunciators.

3. In an annunciator the combination with right and left annunciating arms pivotally suspended, and means for swinging said arms outwardly on their pivots, of a third annunciating arm movable downwardly, means for drawing said third arm downwardly, and a spring connected to each of said right and left arms at one end and at the other end to said third arm whereby movement downwardly of said third arm tenses said springs.

4. In an annunciator the combination with right and left annunciating arms suspended upon pivots disposed in substantially the same horizontal plane, and means for swinging said arms outwardly on their pivots, of a third slidable annunciating arm movable vertically, two springs joined to said third arm by one end and at their outer ends joined respectively to said right and left arms, said springs maintaining all three arms normally in retracted position, and means for sliding the said third arm whereby said springs are tensed.

5. In an annunciator the combination with right and left annunciating arms suspended from spaced pivots which lie in substantially the same horizontal plane, and means for swinging said arms outwardly on their pivots, of a third annunciating arm positioned between the right and left arms and slidably mounted for vertical reciprocation, a pair of springs each secured at one end to said third arm and secured at their outer ends respectively to said right and left arms at points above the point of connection with said third arm, said springs normally maintaining all three arms in retracted position, and means for sliding said third arm downwardly.

6. In an annunciator the combination with right and left annunciating arms suspended from spaced pivots which lie in substantially the same horizontal plane, and means for swinging said arms outwardly on their pivots, of a third annunciating arm positioned between the right and left arms and slidably mounted for vertical reciprocation, a pair of springs each secured at one end to said third arm and secured at their outer ends respectively to said right and left arms at points above the point of connection with said third arm, said springs normally maintaining all three arms in retracted position, means for sliding said third arm downwardly, and an opaque shield covering all of said arms when in their retracted positions.

In testimony whereof I affix my signature.
ROBERT R. METZ.
